Redding, Greeley, O'Shea & Campbell

UNITED STATES PATENT OFFICE

RICHARD H. WARD, OF QUEENS VILLAGE, NEW YORK, ASSIGNOR TO EDWARD C. BOWERS AND CHARLES L. FELDMAN, RECEIVERS FOR WICKWIRE SPENCER STEEL COMPANY, OF NEW YORK, N. Y., A CORPORATION OF MASSACHUSETTS

RADIATOR SHIELD

Application filed August 3, 1929. Serial No. 383,258.

The present invention relates to shields for radiators and embodies, more specifically, a shield which has telescoping sections whereby the same may be easily adjusted to 5 radiators of varying sizes.

The use of radiator shields is becoming quite wide and the ornamental effect produced thereby has been the main factor controlling their production. Little attention 10 has been given to the specific features of construction, through the instrumentality of which the shield is rendered not only ornamental but extremely serviceable and useful as an article of furniture, as well as simple 15 and inexpensive in construction.

The present invention, accordingly, seeks to provide a radiator shield which is artistic and ornamental in design and construction, as well as highly stable when applied to the 20 radiator.

A further object of the invention is to provide a radiator shield having sections which telescope to adapt the cover to varying sizes of radiators.

25 A further object of the invention is to provide a radiator shield of the above character which combines within its elements a water trough.

Further objects, not specifically enumerated above, will be apparent as the invention is described in greater detail in connection with the accompanying drawings, wherein:

Figure 1 is a view in side elevation, partly broken away, and in section showing the radiator shield constructed in accordance with the present invention.

Figure 2 is a plan view, partly broken away, and in section, showing the radiator shield of Figure 1.

40 Figure 3 is a view in section, taken on line 3-3 of Figure 1, and looking in the direction of the arrows.

Figure 4 is a detail view showing the supporting bracket for the shield as it is secured 45 to the radiator.

Referring to the above drawings, *a* designates a radiator having any given number of coils to which the radiator shield is to be applied. Bracket *b* having spaced lugs *b'* 50 are connected by a bolt *b*² which passes

through the lugs, and downwardly extending arms *b*³, carried by the respective brackets *b*, engage under the connecting portion of the radiator between the coils. These arms *b*³ extend in opposite directions and when applied to the radiator, and the bolt *b*² tightened, the brackets *b* are securely attached to the radiator to provide a stable rest for the radiator shield. 55

A radiator shield is shown as comprised of end pieces *c* and *d* which are telescopically engaged by an intermediate section *e*. All of the sections include vertical portions *c'*, *d'* and *e'* which extend downwardly below the plane of the top of the radiator. The 60 tops of the sections project outwardly beyond the vertical portions and may be formed with suitable grating *f* to increase the artistic effect, as well as provide the desired outlets for heated air. 65

Turned up portions *e*² are provided at each side and at either end of the intermediate section *e* and are adapted to rest on the brackets *b*. The brackets *b* are thus positioned upon the radiator in such manner that 70 they will engage these turned up flanges and the shield is thus supported at four points in stable equilibrium. 75

In one of the end sections, herein shown as section *d*, an opening *d*² is formed. A 80 water tray *d*³ having a handle *d*⁴ is received within the opening and is normally supported above the radiator coils in a fashion which will be easily understood from an inspection of Figure 3. 85

It will be understood that the specific shape and construction of the shield may be altered to suit various types of radiators, as well as designs of desired types. The respective sections may be formed from a single piece 90 of metal, as by stamping and any method of manufacture may be adopted without departing from the scope of the invention as defined in the appended claims. 95

I claim as my invention:

1. A radiator shield comprising end sections, an intermediate section telescopically engaging the end sections, the latter telescoping over the intermediate section, supporting brackets secured to the radiator, inwardly 100

extending portions on the intermediate section, downwardly extending portions formed at the inner ends of the last named portions, and struck up arms on the downwardly extending portions lying flush with the inwardly extending portions to engage the brackets.

2. A radiator shield comprising end sections, an intermediate section telescopically engaging the end sections, the latter telescoping over the intermediate section, supporting brackets secured to the radiator, inwardly extending portions on the intermediate section, a water pan telescoping with the intermediate section and seated on the inwardly extending portions, downwardly extending portions formed on the inner ends of the last named portions, and struck up arms on the downwardly extending portions lying flush with the inwardly extending portions to engage the brackets.

This specification signed this 1st day of August, A. D. 1929.

RICHARD H. WARD.
